Primary Examiner — Sandra Morris(74) *Attorney, Agent, or Firm* — Nixon Peabody LLP(57) **CLAIM**

We claim the ornamental design for a "gaming machine," as shown and described.

DESCRIPTION

FIG. 1 is a left isometric view of a gaming machine. FIG. 2 is a right isometric view of the gaming machine shown in FIG. 1. FIG. 3 is a front view of the gaming machine shown in FIG. 1. FIG. 4 is a right cross-sectional view along lines "4-4" shown in FIG. 3; and, FIG. 5 is a top view of the gaming machine shown in FIG. 1. The broken lines shown in dashed form are only for illustrative purposes to show visible environmental structure and form no part of the claimed design.

The right cross-sectional view is a mirror image of the left cross-sectional views along the "4-4" cross-sectional lines, and is included to clarify an exterior shape of the claimed design.

Primary Examiner — Sandra Morris(74) *Attorney, Agent, or Firm* — Nixon Peabody LLP**CLAIM**

We claim the ornamental design for a "gaming machine," as shown and described.

DESCRIPTION

FIG. 1 is a left isometric view of a gaming machine. FIG. 2 is a right isometric view of the gaming machine shown in FIG. 1. FIG. 3 is a front view of the gaming machine shown in FIG. 1. FIG. 4 is a right cross-sectional view along lines "4-4" shown in FIG. 3, and, FIG. 5 is a top view of the gaming machine shown in FIG. 1. The broken lines shown in dashed form are only for illustrative purposes to show visible environmental structure and form no part of the claimed design. The right cross-sectional view is a mirror image of the left cross-sectional views along the "4-4" cross-sectional lines, and is included to clarify an exterior shape of the claimed design.
